UNITED STATES PATENT OFFICE.

JOHN L. GILL, JR., OF PHILADELPHIA, PENNSYLVANIA.

STEAM-BOILER HOUSE.

SPECIFICATION forming part of Letters Patent No. 408,172, dated July 30, 1889.

Application filed October 3, 1888. Serial No. 287,084. (No model.)

To all whom it may concern:

Be it known that I, JOHN L. GILL, Jr., a citizen of the United States, residing at Philadelphia, in the county of Philadelphia and State of Pennsylvania, have invented certain new and useful Improvements in the Art of Constructing Steam-Boiler Houses; and I do hereby declare the following to be a sufficiently full, clear, and exact description thereof as to enable others skilled in the art to make and use the said invention.

This invention relates to the arrangement of batteries of steam-boilers or steam-generators in plants requiring large aggregations of steam-generating capacity, and has for its object economy of space, economy of labor in attendance, and the facility of access for cleaning and repairs.

To effect these several desiderata this invention consists of a combination in one structure of a fuel receiving and storage apparatus, a fuel-distributing apparatus, and an ash collecting and discharging apparatus, with building, furnace, and boiler constructions adapted thereto, as hereinafter described, and as shown in the accompanying drawings, by means of which the most simple plan of handling, storing, and distributing of fuel and the collecting and removal of ashes from the furnaces is effected, the expenses of labor in operating the plant are reduced to a minimum, a perfect and regular supply of fuel to each boiler-furnace is secured, and perfect cleanliness of the building is obtained.

Figure 1 shows a transverse vertical section of a three-story boiler-house; Fig. 2, a lengthwise vertical section of the same.

The same reference-marks indicate like parts in both figures.

40 A', A², A³, and A⁴ represent boilers or steam-generators resting on the ground floor, and may be either water-tube boilers or return-tubulars; B', B², B³, and B⁴, steam-generators in similar settings on the second floor.

45 C' and C² are nests of economizers on the third floor.

D is a chimney, which may be made of metal throughout or masonry throughout, but preferably in brick or masonry, extending 50 above the roof-line of the building and there contracted and supplemented by a cylindrical metallic stack D'.

D' is the extension of the chimney above the roof, which may be made of metal or masonry.

55 D² are vertical divisions of the flues E', E², E³, E⁴, and F', F², F³, and F⁴, which are desirable but not essential.

D³ is a partition-wall, which extends centrally from the bottom of the chimney to a point above the level of the second-story battery of boilers, or, in case the economizers are used, to a point above the level of the upper part of the economizers C' and C².

60 E', E², E³, and E⁴ are flues leading laterally from the furnaces A', A², A³, and A⁴ to the base of the stack D, which is expanded at the point of the intersection of the flues F', F², F³, and F⁴, so that at this point the chimney is equal in cross-sectional area of the 70 several flues E', E², E³, and E⁴, and F', F², F³, and F⁴.

75 G G are lateral flues for conducting the heat and waste gases from the chimney to the rear end of the economizers.

75 G' G' are openings in the stack, through which the gases pass into the flues G G.

H H are dampers, which close the openings G', when in a vertical position, and allow the products of combustion to directly ascend 80 the stack D, or, when in a cross position, close the stack above the opening G', so as to turn the gases into the flues G G.

85 As above described, the apparatus for draft-distribution is the subject of claims in a distinct application for Letters Patent, serially numbered 287,085, filed on the 3d day of October, 1888, and is here shown and described to afford a clearer understanding of the fuel storage and distribution and ash collecting 90 and discharging apparatus and the furnace construction adapted thereto and the relation of these parts to the spaces and passage-ways for affording access to the several portions of the plant.

95 J' and J² are the longitudinal walls of the boiler-house.

K is the ground-floor.

K' is the second-story floor.

K², the third-story floor.

L is the roof of the building.

100 M is a coal dump or hopper under the railroad track outside of the building, where coal is received by gravity from the cars.

M' is a chute to carry the coal to the boot of the elevator.

M³ is the lower wheel of an endless-chain elevator; M⁴, the endless chain bearing the 5 scoops; M⁵, the scoops; M⁶, the upper wheel on a driving-shaft in the upper story of the building.

M⁷ is a funnel for directing the coal into the trough M² of the cross-conveyer; M⁸ and 10 M⁹, hoppers for delivering the coal into the longitudinal conveyers V V; M¹⁰, scoops on the endless chain M¹¹; M¹¹, endless chain of the cross-conveyer.

A spiral conveyer, as shown at O, Fig. 2, 15 may be used instead of the endless-chain conveyer M¹¹ M¹¹, which is used to convey the coal to either of the longitudinal conveyers V V through the hoppers M⁸ or M⁹.

M¹² and M¹³ are storage-bins for receiving 20 coal and storing same till needed, and should be made large enough to hold at least one week's supply of coal; M¹⁴ and M¹⁵, hopper-bottoms of the coal-bins, through which the coal feeds by gravity to the pipes M¹⁶ and M¹⁷; 25 M¹⁶ and M¹⁷, pipes for conveying coal by gravity to the hoppers of the automatic stokers.

M¹⁸ are gates by which the supply of coal to the stokers is controlled; M²⁰ and M²¹, hoppers of the automatic stokers; N' and N², furnaces of the automatic stokers, which may have common flat grates; but inclined reciprocating grates are preferably used, the furnace shown being for the well-known W. P. Roney stoker.

35 N³ and N⁴ are troughs through which the spiral conveyers O, Fig. 2, or the endless-chain conveyers O' O² pass while removing the ashes that fall into them.

O, Fig. 2, is a spiral conveyer, which may 40 be used instead of the chain conveyers O² O².

O' O² are the paddles or scoops on the endless-chain conveyers O².

O² O² are the endless-chain conveyers used to remove the ashes from the several furnaces in which they are made, and to discharge them directly into the ash-bins W (through the chute W') or into the boot O⁸ of the elevator O⁴. These endless chains O² are returned over the furnaces when the furnaces 45 project far enough in front of the boilers, as shown at boiler A³; otherwise they are returned over the boilers, as shown at boiler B³.

O³ is the lower wheel of the endless-chain elevator O⁴.

50 O⁴ is the endless-chain elevator used to raise the ashes from the boot O⁸ and discharge them into the bins W through the chute O⁷.

O⁵ are the buckets on the elevator-chain.

60 O⁶ is the upper driving-wheel of the elevator O⁴.

O⁷ is a chute through which the ashes pass into the bins W from the elevator O⁴.

65 P P are intermediate floors placed at the level of the hoppers M²⁰ and M²¹, affording access at a convenient level to the hoppers

M²⁰ and M²¹, and also to the upper portion of the boiler-fronts, and leaving spaces or passage-ways Q at the level of the furnace-floors.

70 Q Q are passage-ways used by the firemen in taking care of the grates and ash-conveyers.

R R are passage-ways under the flues E', E², E³, and E⁴, and F', F², F³, and F⁴ at the rear 75 of the boilers, affording easy access to the rear end of the boiler-settings and to the tubes of the boilers.

S are doors for closing the openings in the boiler-settings, which openings afford access to the tubular part of the boilers.

V V are troughs of the longitudinal conveyers.

V' V' are the longitudinal conveyers.

Having described the construction and operation of this invention, what I claim is—

1. The described boiler-plant, having superposed fuel-storage bins and elevators, and horizontal conveyers arranged to raise and distribute fuel to said bins, combined with 90 hoppers located at a lower level and pipes provided with adjustable gates for distributing fuel by gravitation and regulating the supply thereof from said storage bins and hoppers into the several furnaces, substantially as set forth and shown.

2. The described boiler-plant, having fuel-storage bins provided with hoppers and pipes having adjustable gates therein for distributing fuel to the several furnace-hoppers 100 enclosed within a building having floors affording access to the furnace-hoppers located intermediately between the boiler-supporting floors and covering air-conduits to the ash-pits, substantially as set forth.

105 3. In a boiler-plant, the combination of the furnace, provided with feeding-hoppers, with the described fuel elevating and distributing apparatus and storage-bins located above the furnace-levels, with tubes leading to the several furnace-hoppers, and ash-conveyers arranged to continuously remove ashes from the several furnaces, substantially as set forth and described.

110 4. The combination of self feeding and stoking furnaces arranged in series horizontally, with conveyers to continuously remove the ashes from the ash-pits of the several furnaces, floors located intermediately between the supporting-floors and ceilings of the boiler-rooms, arranged to afford access to the fuel-feeding hoppers of the furnaces and to form conduits for air to the ash-pits excluding ash-dust from the furnace and boiler rooms, substantially as set forth.

115 5. In a boiler-plant, the combination of the described fuel elevating and distributing apparatus with one or more series of boilers arranged in a line and provided with a horizontally-operating ash-conveying mechanism, 120 which continuously removes the ashes from the entire line of furnaces at the same level,

and an ash elevating and discharging apparatus, arranged substantially as and for the purpose set forth.

6. The combination, in the boiler-plant, of several boilers arranged in parallel positions, with a single horizontally-operating ash-conveyer for continuously removing the ashes from the ash-pits of the entire series, with an

elevator for removing the ashes from the conveyer to an ash-storing bin, substantially as set forth and shown.

JOHN L. GILL, JR.
